UNITED STATES PATENT OFFICE

THEODORE L. CHISHOLM, OF DAYTON, OHIO, ASSIGNOR, BY MESNE ASSIGNMENTS, TO
FRIGIDAIRE CORPORATION, A CORPORATION OF DELAWARE

REFRIGERATING APPARATUS

Application filed January 31, 1927. Serial No. 164,746.

This invention relates to cooling units for mechanical refrigerators, and more particularly to cooling units which are adapted to be installed in refrigerating cabinets of the household type. However, it is to be understood that the present invention may be adapted for refrigerating apparatus of other types.

It is among the objects of the present invention to provide a cooling unit of simple and economical structure, which will quickly congeal or freeze substances placed within a freezing compartment provided by the unit, and which will effectively cool the food compartment of the cabinet.

Another object is to improve the efficiency of the cooling unit by reducing its tendency to become coated with frost.

Further objects and advantages of the present invention will be apparent from the following description, reference being had to the accompanying drawings, wherein a preferred form of embodiment of the present invention is clearly shown.

In the drawings:

Fig. 1 is a front view of a refrigerator cabinet with the door open in order to show the food compartment and a cooling unit within a cooling compartment;

Fig. 2 is a view on a larger scale than Fig. 1, showing the front view of the cooling unit supported within the cooling compartment of a cabinet, the walls of which are shown in vertical section;

Fig. 3 is a side elevation of the cooling unit drawn to the same scale as Fig. 2; and

Fig. 4 is a fragmentary detail sectional view taken along the lines 4-4 of Fig. 2.

Referring to the drawing, 20 designates a refrigerating cabinet having an L-shaped food compartment 21 separated from a cooling compartment 22 by horizontal partition 23 and a vertical partition 24. The partition 24 is provided with a flue 25 which admits relatively warm air from the food compartment 21 to the cooling compartment 22. Partition 23 provided with a flue 26 admits cooled air from the compartment 22 to compartment 21. The partition 23 supports a baffle 27 which prevents any moisture which

should happen to drip from the cooling unit above from entering the flue 26. The baffle 27 directs such moisture upon the upper surface of the partition 23, from which it is conducted away by a drain pipe 28.

The cooling unit located within the cooling compartment 22, includes a boiler or header 30 attached to the top wall of cabinet by bracket members 31 and 32. Liquid refrigerant is conducted to the header 30 from a compressor and condenser, not shown, through a pipe 33 and a fitting 34. Refrigerant is admitted from the fitting 34, as needed, by a float controlled valve, not shown, located within the header 30. Expanded refrigerant is conducted to the compressor through a fitting 35 and a pipe 36. The refrigerating compressor and condenser with which the pipes 33 and 36 communicate may be located outside of the cabinet, if desired, or may be placed within a machine compartment located below the food compartment 21, said compartment having a removable wall 37 provided with louvers 38.

The cooling unit includes a plurality of ducts 40 and 41, of elongated cross section and preferably arranged in longitudinal rows along the header. The elongated section of the ducts provides a relatively large surface area and a relatively small volume, which reduces the quantity of refrigerant required to produce a given amount of cooling. The ducts 40 of the two inside rows provide a freezing zone or space 42 which may contain one or more metal sleeves 43 for the reception of freezing trays 44. The loops 40 are arranged with their flat sides in alignment so as to bring the ducts close together and occupy as much of the side of the freezing space as possible. Preferably the flat sides are soldered to the sleeves, and thus provide a large heat exchange area in contact with the sleeves.

In order to facilitate proper sliding of the trays inside the sleeves the bottom wall of each sleeve may be provided with a plurality of extending portions 43a providing slides for said trays.

Ducts 41 depending from the header extend outwardly into the cooling chamber, 100

- remote from the freezing space and ducts 40. The ducts also have an elongated cross-section, but the flat sides are perpendicular to the direction of the rows, in order to increase the distance between adjacent ducts. Likewise the ducts 41 are spaced between ducts 40 along the length of the header to increase the distance between ducts 40 and 41.
- 10 Manufacture and assembly of the cooling unit are considerably cheapened and facilitated by making the ducts in pairs, in the form of equally spaced U-shaped loops one arrangement of which is shown in Fig. 3.
- 15 Equally spaced round holes are formed in the header and the upper end of each duct has a rounded portion 45 which fits into a hole. Thus while the ducts are equally spaced along the header at their points of attachment thereto, the inner ducts 40 are relatively close together throughout their length, and the outer ducts 41 are relatively far apart.
- The distance apart of the ducts 41 decreases the likelihood of frost bridging over between ducts, which, if it formed, would prevent air from circulating between them and would therefore decrease their cooling efficiency.
- 20 Moreover frost can be prevented from building up to any great thickness on the ducts 41 by setting the control of the compressor which supplies the liquid refrigerant to this unit so that the compressor begins operating and starts withdrawing the refrigerant vapor through the pipe 36 only after the ducts 40 and 41 reach a temperature slightly above freezing point, for instance $32\frac{1}{2}$ ° F. The compressor will then continue to operate until the refrigerant in the cooling unit reaches a desired minimum temperature, for instance $12\frac{1}{2}$ ° F., when automatic controls will stop the compressor. Such automatic controls for starting and stopping the compressor at the desired maximum and minimum temperature are well known in the art and hence will not be herein described. Now during the greater portion of one complete cycle of such a system the refrigerant in the cooling unit will be greatly below freezing point and hence frost will form and build up on the outside of the entire unit. However, during that part of the cycle when the refrigerant is at a temperature at or slightly above freezing point this frost will be melted by the circulating air which ordinarily is considerably above the freezing point. Since the circulating air comes into intimate contact with the exposed portions 41, these portions can be defrosted at each cycle. However, the ducts 40, being much less exposed to the circulating air and having a large duct surface within a relatively small compact space will not be defrosted at each cycle.
- 25 Therefore, frost can gradually build up all

around these ducts and form a shield around the freezing space against the circulating air. Hence the refrigerant in the ducts may have a maximum temperature slightly above 32° F. for a short period of time without tending to melt the ice in the trays 44 since the accumulated body of frost will maintain their temperature at 32° F. during this short period. It is obviously very advantageous to defrost the portions 41 during each cycle, since these portions form a very large part of the air-cooling surface of the unit, and still to permit the cooling surface for the freezing compartments to retain frost continuously.

While the form of embodiment of the present invention as herein disclosed, constitutes a preferred form, all coming within the scope of the claims which follow.

What is claimed is as follows:

1. A cooling unit for a refrigerator comprising a refrigerant supply member and refrigerant ducts connected to said member and co-operating to provide a freezing zone, an ice tray support adapted to support an ice tray within said zone, said ducts being of elongated cross-sectional shape, the broader sides being adjacent said freezing zone and thermally connected with said support.

2. A cooling unit for a refrigerator having cooling and freezing spaces comprising a refrigerant supply member and refrigerant ducts leading therefrom, certain of said ducts co-operating to enclose the freezing space, said ducts being of elongated cross-sectional shape, the broader sides lying adjacent the freezing zone, the other ducts extending into the cooling space of the refrigerator.

3. A cooling unit for a refrigerator having freezing and cooling spaces comprising a refrigerant supply member and conduits in the form of loops extending therefrom, portions of said loops being elongated in cross section and having their broader sides adjacent the freezing space.

4. A cooling unit for a refrigerator having freezing and cooling zones comprising a refrigerant supply member and conduits in the form of loops extending therefrom, said conduits being elongated in cross-section and having the broader sides of some of said conduits providing the freezing zones, the broader sides of the other conduits being arranged angularly to the broader sides of the first mentioned conduits and lying outwardly of the freezing zone to provide a cooling zone.

5. A cooling unit for mechanical refrigerators comprising, a refrigerant supply member and a plurality of rows of conduits elongated in cross section communicating with said member, some of said conduits being arranged so that the broader sides of the conduits co-operate to provide a freezing zone, other of said conduits being located so as to be substantially entirely exposed to air adjacent the cooling unit.

6. A cooling unit for mechanical refrigerators comprising, a refrigerant supply member and a plurality of U-shaped conduits communicating with said member, said conduits including branches and connecting yoke portions, both portions being of an elongated cross-sectional shape, some of said conduits being arranged in parallel rows so that the broader sides of the branches lie in a plane parallel with the axis of refrigerant supply member and co-operate therewith to provide a freezing zone and other of said U-shaped conduits having their branches spaced from the freezing zone so as to be entirely exposed to air adjacent the cooling unit. 15
7. A cooling unit for mechanical refrigerators, comprising a refrigerant supply member and a plurality of U-shaped conduits including branch portions and a connecting yoke portion, both portions being of an elongated cross-sectional shape, certain of the conduits having their broader sides in alignment so as to co-operate to provide a freezing zone and the other conduits having their broader sides arranged angularly to the first mentioned conduits and being spaced remote from said freezing zone. 20
8. A cooling unit for mechanical refrigerators comprising, a refrigerant supply member and a plurality of conduits of an elongated cross-sectional shape certain of said conduits having their broader sides aligned so as to provide a freezing zone, the broader sides of the other conduits being arranged at right angles to the broader sides of the first mentioned conduits and spaced remote from the freezing zone, the remote conduits lying in planes passing midway between the first mentioned conduits. 25
9. A cooling unit for mechanical refrigerators including freezing and cooling zones and comprising, an elongated header and a plurality of conduits of elongated cross section depending from said header, the broader sides of certain conduits being aligned parallel with the axis of the header and co-operating with said header to provide the freezing zone. 30
10. A cooling unit for mechanical refrigerators including freezing and cooling zones comprising an elongated header and a plurality of conduits of elongated cross-section depending from said header, the broader sides of certain conduits being aligned parallel with the axis of the header and co-operating with said header to provide the freezing zone, the other of said conduits being arranged so as to have their broader sides at right angles to the first mentioned conduits and being spaced remote from the freezing zone. 35
11. A cooling unit adapted to be placed in the path of the medium to be cooled thereby, said cooling unit including heat exchange means in intimate contact with a refrigerant and with said medium to be cooled, said heat exchange means including a portion provid- 40
- ing a freezing zone, a support in intimate thermal contact with said portion and adapted to support an ice tray within said freezing zone, and a plurality of duct portions of elongated cross sections disposed angularly of the freezing zone and providing a cooling zone for said medium, said last portions lying outwardly of the freezing zone with the broader sides of said portions in intimate thermal association with the medium flowing thereover. 45
12. A cooling unit for cooling circulating air in a refrigerator cabinet comprising a header adapted to contain refrigerant, heat exchange means in intimate contact with the refrigerant and the medium to be cooled, said heat exchange means including elongated portions arranged in a plurality of rows disposed longitudinally of the header, the broader sides of the elongated portions of one row being arranged in alignment, and the broader sides of the elongated portions of another row being arranged transverse to the broader sides of the first row. 50
13. A cooling unit for cooling circulating air in a refrigerator cabinet comprising heat exchange means in intimate contact with a refrigerant and with the medium to be cooled, said heat exchange means including a plurality of elongated portions arranged in a plurality of rows, the broader sides of the elongated portions of one row being arranged in alignment, and the broader sides of the elongated portions of another row being arranged transverse to the broader sides of the first row. 55
14. A cooling unit for refrigerating apparatus comprising heat exchange means in intimate contact with a refrigerant and with the medium to be cooled, said heat exchange means including a plurality of elongated portions arranged in a plurality of rows, the broader sides of the elongated portions of one row being arranged in alignment, and the broader sides of the elongated portions of another row being arranged transverse to the broader sides of the first row and disposed in planes between the portions of the first row. 60
15. A cooling unit for refrigerating apparatus comprising a header and a plurality of ducts extending therefrom, portions of the heat absorbing surfaces of some of the ducts being relatively closely spaced from one another and provide a freezing zone adapted to receive an ice tray, and heat absorbing surface 115 of other of the ducts providing a cooling zone, said last ducts lying outwardly of the freezing zone and being relatively widely spaced from one another. 120
16. A cooling unit for refrigerating apparatus comprising a header and a plurality of rows of ducts extending therefrom, portions of the heat absorbing surfaces of the ducts in one or more of the rows being relatively closely spaced from one another and 130

provide a freezing zone adapted to receive an ice tray and portions of the heat absorbing surface of the ducts in one or more other rows providing a cooling zone, said last ducts 5 lying outwardly of the freezing zone and being relatively widely spaced from one another.

17. A cooling unit for cooling circulating air in a refrigerator cabinet comprising a 10 plurality of flat ducts, the broader sides of certain of said ducts being arranged lengthwise of one another and cooperate to provide a freezing zone, and certain of said ducts being arranged in more intimate thermal relation with the air flowing thereover, the broader sides of said latter ducts being arranged transversely of the broader sides of the first ducts.

18. A cooling unit for cooling circulating 20 air flowing thereover comprising a plurality of ducts, portions of said ducts being flat and the broader sides thereof being arranged lengthwise of one another and cooperate to provide a freezing zone, and portions of said 25 ducts being arranged in more intimate thermal relation with the air flowing thereover, said latter portions being flat and having the broader sides thereof arranged transversely of the broader sides of the first portions.

30 In testimony whereof I hereto affix my signature.

THEODORE L. CHISHOLM.
